UNITED STATES PATENT OFFICE.

ISAAC WOLF, OF MILWALL, LONDON, ENGLAND.

LOOSE-LEAF BINDER.

1,216,532.

Specification of Letters Patent. Patented Feb. 20, 1917.

Application filed April 5, 1916. Serial No. 89,025.

To all whom it may concern:

Be it known that I, ISAAC WOLF, a subject of the King of Great Britain, residing at 304 West Ferry road, Milwall, in the 5 county of London, England, have invented certain new and useful Improvements in or Relating to Loose-Leaf Binders, of which the following is a specification.

This invention relates to improvements in 10 loose leaf binders.

The object of the invention is to produce an improved construction of loose leaf binder in which the usual telescoping filing posts are dispensed with and in which simple and efficient means are provided for locking the clamping bars in their closed position and unlocking the same when desired for the insertion or withdrawal of the loose leaves.

According to the present invention the back of the binder case is divided longitudinally into two separable parts, said parts being preferably constituted by a pair of L-shaped metal clamping members, each 25 clamping member being attached to one of the covers of the binder.

The short ends of the L-shaped members (as distinguished from the ends which carry the binder covers) constitute the back of 30 the binder and are adapted to be normally locked in contact with one another. The locking means are preferably constituted by locking lugs provided on one of the faces of the short ends of the L-shaped members, 35 which locking lugs when the binder is closed fit into slots provided in the adjacent face of the other L-shaped member; a spring pressed sliding bar being provided adapted to engage the lugs automatically immediately 40 they are pressed home into the said slots.

To unlock the clamping members, the sliding bar is adapted to be moved laterally by means of a key so as to disengage the 45 sliding bar from the locking lugs. The clamping members can then be moved apart to a limited extent. The filing posts are constituted by two or more bars located transversely of the binder covers and adj- 50 cent to the back of the binder. The said filing posts and the clamping members are capable of limited endwise movement relative to one another so as to allow the clamping members to be moved apart to a limited 55 extent to permit of the insertion or withdrawal of the loose leaves.

In practice I prefer to allow $\frac{5}{8}$ " when the clamping bars are open between each extremity of the filing post and the inner ends of the recesses in which they are located so 60 that the clamping bars when unlocked can be separated for a distance of $1\frac{1}{4}$ ".

To prevent the ends of the filing posts being withdrawn from the recesses, I may provide bosses or bolt heads on their extremities and close up the outer side of the recesses by means of closure plates which embrace the filing posts and are secured by means of screws to the clamping members.

If desired I may locate springs between 70 the extremities of the filing posts and the base of the recesses, so as to cause the clamping bars to move apart automatically immediately the locking device is actuated. In order not to produce any unnecessary thick- 75 ening of the clamping bars, I prefer, however, to dispense with such springs in connection with the filing posts, and in cases where automatic separation of the clamping bars is desired, I employ in lieu thereof two 80 or more strengthening posts which may be located at any convenient part of the clamping members, but preferably toward the ends thereof. I prefer to employ strengthening posts of the type having one extremity attached to one of the inside faces of the clamping members, the other extremity being located within a recess in the adjacent face of the other clamping member. The extremity of each of the strengthening posts 85 is free to move in an endwise direction within the said recess for a distance corresponding to the total endwise movement of the filing posts *e. g.* one and a quarter inches. Within each of the said recesses I provide a 90 helical spring which bears on the extremity of each of the strengthening posts and causes the clamping bars to move relatively to the said posts immediately the clamping bars are released by the actuation of the 95 locking means.

Alternatively I may dispense with the use of spring actuated strengthening posts and construct the various parts so that the separation of the clamping members is effected when the latter are unlocked. For this purpose I provide means controlled by the action of opening the binder. This modified construction of my invention has the advantage that the clamping bars, after 105 being unlocked, move apart by a progressive movement as the binder is opened, instead

of springing apart suddenly when the binder is interlocked as occurs in the first mentioned arrangement.

To provide additional security against extraction of the binder leaves when the binder is locked I may employ one or more composite filing posts constructed as hereinafter described in lieu of or in addition to the usual filing posts.

10 Two preferred embodiments of the invention are illustrated in the accompanying drawing in which:—

Figure 1 is an elevation of the clamping bars.

15 Fig. 2 is a plan of the lower clamping member.

Fig. 3 is a cross sectional end-view on an enlarged scale, taken through the center of the clamping bars when in the closed position.

20 Fig. 4 is a longitudinal section of the modified construction of binder.

Fig. 5 is a cross sectional view on the line x, y of Fig. 4.

25 Fig. 6 is a detail view showing the location of the end of one of the filing posts in the embodiment shown at Figs. 4 and 5.

Fig. 7 is a detail view showing the slot in one of the clamping bars for accommodating one end of one of the composite filing posts.

30 Fig. 8 is a view showing one of the said composite filing posts.

Fig. 9 is a longitudinal section of the locking bar; and

Fig. 10 is a section on the line X—Y of Fig. 9.

Referring to the Figs. 1, 2 and 3 of the drawings, 1 indicates the clamping members which are constituted by a pair of L-shaped plates; 2 are the filing posts; 3 are the recesses in which they are located; 4 are nuts provided on the ends of the filing posts to prevent them being withdrawn from the recesses 3; 5 are the closure plates for the recesses; 6 are the strengthening posts; one extremity 7 of each of which is screwed into the inside face of one of the clamping members. The other extremity 8 of each 45 strengthening post is located in a recess 9 in the adjacent face of the other clamping member; 10 are helical springs which bear on one extremity of each of the strengthening posts. 11 are locking lugs which engage slots 12 in the adjacent face of the clamping member; 13 is a locking device of the type comprising a spring pressed member adapted to engage the lugs 11 automatically immediately they are pressed home 50 into the slots 12; 14 is a key for actuating the locking device. In order to reduce the weight of the clamping members bosses 15 are provided in the clamping bars so as to reduce their thickness and furnish the additional space necessary for the movement of 55

the clamping bars relative to the filing posts.

In the modified construction of loose leaf binder shown at Figs. 4 to 10 the binder comprises a pair of clamping bars 16, 16 adapted as before to be retained in contact with one another by means of a sliding locking bar 17. 42 are locking lugs which, in the locking position, engage slots 43. The locking bar 17 has a helical spring 44 which bears on one of its extremities. 45 is a central opening in the bar 17 into which a key 46 is adapted to be inserted and engage the pin 47, so that by rotating the key, the bar 17 is moved in the direction of the arrow in Fig. 9, thus disengaging the locking lugs 42 from the slots 43 and permitting the binder to be opened. In this construction of binder, however, the use of either spring pressed filing posts or strengthening bars is dispensed with. The filing posts 18 of which two are shown are capable as before of limited movement relatively to the clamping bars 16, 16 when the binder is open, while the strengthening bars 19 of which two are shown are carried on supports 20, their inner ends 19^a projecting beyond the said supports, so that the bars 19 can also slide to a limited extent within the supports 20 when the binder is open. In order to produce the desired movement of the clamping bars 16, 16 relatively to the filing posts 18 and the strengthening posts 19, the ends of each of the said bars 19 carry pins 20^a, adapted to slide in slots 21 in the bifurcated end 23 of the cranked lever 22. Each lever 22 has a pivot pin 28, carried on supports 29 forming part of one of the clamping bars 16, and comprises an upper arm 24 rigidly connected by means of a screw 25 to the member 26 forming part of the support for the side 27 of the binder, and a lower bifurcated end 23 which embraces the strengthening post 19, each arm of which end 23 is slotted as aforesaid so as to engage the pin 20^a on the strengthening post 19. The clamping bars 16, 16 are provided with slots 16^a and it will be understood that in view of this arrangement and when the clamping bars are unlocked the cranked levers 22 will swing about 105 their fulcrums or pivotal centers 28 when the sides 27 of the binder are opened, and the clutches hereafter to be described are in engagement, to the position shown in dotted lines at Fig. 5, the strengthening posts being thereby caused to move relatively to the clamping bars 16, 16 thus moving the latter apart and releasing the loose leaves in the binder. In order to permit the binder to be opened for ordinary use without this 110 relative movement of the clamping bars and strengthening posts, which of course is only desired at comparatively rare intervals, means are provided so that it can only take place when desired. To this end each of the 115

members 26 may be provided with a pair of clutch devices which require to be actuated by an endwise movement of the binder sides before the cranked levers can effect any relative movement of the parts. Each of the frames 30, one of which only is shown at Fig. 4, which carry the binder sides 27 (shown in dotted lines in Fig. 4) are formed with sleeves 31, 31^A, which are mounted on reduced parts 32 of the members 26. The sleeve 31 has a protuberance 31^B adapted when the frame 30 is moved in the direction of the arrow to engage a recess 33 on the outer end 35 of the member 26. The sleeve 31^A, is also formed with a protuberance 31^C located within a recess 31^D in the member 26, a spring 31^E being provided between the end of the protuberance 31^C and the inside of the recess 31^D, so as normally to hold the protuberance 31^B out of engagement with the recess 33. To permit the parts to be assembled the ends 35 of the members 26 may be detachable and formed with screw threads 36.

25 Referring more particularly to Fig. 8, 37 is the composite post which in the embodiment shown is built up of five stock sections, namely, a central part 38 and four end parts of the form shown at 39 and 40. The outer 30 ends of the parts 39 and 40 fit into recesses 41 (Fig. 7) in the clamping bars and when the clamping bars are open, any one of these parts can by an endwise movement be slid out of engagement with the adjacent part so 35 as to permit one or more of the loose leaves which are threaded on the said post to be extracted from or inserted in the binder. Although a clamping post composed of three parts only has been shown, any number of 40 similar parts can be employed as it will be obvious that on account of the manner in which the sections shown are constructed they can be coupled together end to end to form a post of any desired length.

45 The loose leaves are attached to the filing posts by unlocking the clamping bars, inserting the leaves on the filing posts, and on the center post where such is provided. When the predetermined number of sheets 50 for which the binder is constructed are located in position on the posts, the clamping bars are pressed together and the binder locked.

What I claim and desire to secure by Letters Patent of the United States is:—

1. A loose leaf binder comprising a pair of clamping bars, means for normally retaining said clamping bars in contact with one another, a plurality of filing posts carried by said clamping bars, and means for displacing said clamping bars relatively to said filing posts to a limited extent.

2. A loose leaf binder comprising a pair of clamping bars, means for normally retaining said clamping bars in contact with

one another, a plurality of filing posts carried by said clamping bars, strengthening means carried by said clamping bars, and means for displacing said clamping bars to a limited extent relatively to said filing posts and said strengthening means.

3. A loose leaf binder comprising clamping bars, means for normally holding said clamping bars in contact, a plurality of filing posts, a plurality of strengthening posts, and means for displacing said clamping bars to a limited extent relatively to said filing posts and said strengthening posts.

4. A loose leaf binder comprising clamping bars, means for normally retaining said clamping bars in contact, filing posts composed of parts capable of endwise movement relatively to one another and to said clamping bars, and means for displacing said clamping bars to a limited extent relatively to said filing posts.

5. A filing post for a loose-leaf binder consisting of a plurality of stock sections assembled end to end and slideable with relation to each other so that each section may be displaced relatively to the remaining sections.

6. A loose leaf binder comprising a pair of clamping bars, means for normally retaining said clamping bars in contact, solid filing posts carried by said clamping bars, strengthening posts carried by said clamping bars, a built up filing post composed of parts capable of endwise movement relatively to one another, and means for displacing said clamping bars to a limited extent relatively to said solid filing posts, said strengthening posts, and said built up filing post.

7. A loose leaf binder comprising a pair of clamping bars constituting the back of the binder case, locking means carried by said clamping bars for normally maintaining them in contact with one another, members constituting the sides of said binder case hingedly connected to said clamping bars, means for releasing said locking means, and means for displacing the said clamping members to a limited extent in opposite directions upon the said hinged members being opened outwardly.

8. A loose leaf binder having a back divided longitudinally into two separable parts, binder sides attached to each of said separable parts, means for normally maintaining said separable parts in contact, and means controlled by the movement of the binder sides for displacing said separable parts to a limited extent relatively to one another when the binder is opened.

9. A loose leaf binder having a back divided longitudinally into two separable parts, binder sides attached to each of said separable parts, filing posts and strengthening posts carried by said separable parts,

locking means for normally maintaining said separable parts in contact with one another, means for releasing said locking means, and means controlled by the movement of the binder sides for displacing said separable parts relatively to said filing posts, and said strengthening posts.

10. A loose leaf binder having a back divided longitudinally into two separable parts, binder sides hingedly connected to each of said separable parts, locking means for normally maintaining said separable parts in contact, means for normally permitting said binder sides to be opened without displacing said separable parts, means for releasing said separable parts, and means actuated by an endwise movement of the said binder sides for displacing said separable parts to a limited extent relatively to one another when the binder sides are again opened.

11. A loose leaf binder having a back divided longitudinally into two separable parts, locking means for normally maintaining said separable parts in contact, filing posts carried by said separable parts, a strengthening post, bars extending longitudinally of said separable parts, cranked levers, each having a slotted arm, pivotally connected to each of said separable parts, one arm of each lever extending through an elongated slot in the said separable parts and being connected to each of said bars, pins carried at the extremities of the said

strengthening posts engaging within the slots in said lever arms, binder sides pivotally attached to each of said bars, means for releasing said separable parts, and means actuated by an endwise movement of the binder sides, on the release of the said locking means, for rocking said cranked levers and gradually forcing said separable parts apart as the binder is opened.

12. A loose leaf binder having a back divided longitudinally into two separable parts, locking means for normally maintaining said separable parts in contact with one another, filing posts and strengthening posts carried by said separable parts, bars extending longitudinally of said separable parts, cranked levers each having a slotted arm pivotally connected to each of said separable parts, one arm of each lever extending through an elongated slot in the said separable parts and being connected to each of said bars, pins carried at the extremities of the said strengthening posts engaging within the slots in said lever arms, binder sides pivotally connected to each of said bars, means for releasing said separable parts, and means actuated by an endwise movement of the said binder sides after the release of the said locking means and by the action of opening the binder for rocking said cranked levers and gradually forcing said separable parts apart.

ISAAC WOLF.
